UNITED STATES PATENT OFFICE.

PHILETUS W. GATES, OF EVANSTON, ILLINOIS, ASSIGNOR TO MUMFORD MOLDING MACHINE COMPANY, A CORPORATION OF NEW JERSEY.

MOLDING-MACHINE.

1,385,676.

Specification of Letters Patent. Patented July 26, 1921.

Application filed May 10, 1920. Serial No. 380,119.

To all whom it may concern:

Be it known that I, PHILETUS W. GATES, a citizen of the United States, residing at Evanston, in the county of Cook and State 5 of Illinois, have invented certain new and useful Improvements in Molding-Machines, of which the following is a specification.

This invention relates to improvements in molding machines and has for its object to 10 provide a new and improved type of combination machine, as it is termed, *i. e.*, a machine which will perform both jolting and squeezing operations.

In my improved machine I am enabled to 15 utilize a single plunger coacting with a cylinder having a central upstanding post without locating the jolt valve mechanism upon said post, but otherwise compactly locating it so that it may be readily removed 20 for inspection or test without requiring the disassembling of the entire machine.

Another advantage of my improved machine lies in the fact that I provide constant communication between the inner jolting 25 cylinder and the recess in the plunger into which the automatic jolt valve projects, thereby preventing premature closing of the jolt valve, as will be more fully described.

These and other objects will be more fully 30 set forth and described in the accompanying drawings in which—

Figure 1 is a vertical section of my improved machine, a portion of the jolt valve being shown in elevation.

Fig. 2 is a rear elevation of the same.

Fig. 3 is a detail section along the line 3—3 of Fig. 4.

Fig. 4 is a horizontal section along the line 4—4 of Fig. 2.

Like numerals refer to like elements throughout the drawings in which 10 indicates generally a hollow base member having a supporting flange 10^a upon which rests and is secured the cylinder and piston 40 mechanism described below. This mechanism comprises a main cylinder 11 having the outwardly extending peripheral flange 11^a resting upon and secured to the flange 10^a, see Fig. 1. A cylinder head 12 is se- 45 cured by bolts 13, or the like, to the cylinder 11 being shown as formed with a central upstanding post 12^a provided with suitable grooves 12^b and piston rings 14, see Fig. 1.

The cylinder 11 is further provided with the 50 tubular port 11^b in which is seated an automatic jolt valve block shown as of the Mum- 55

ford-Huggins type, briefly, comprising an air inlet 15^a and an air outlet 15^b. At its inner portion the block is further provided with the chambers 15^c, 15^d connected by a vertical passage 15^e having the valve seat 15^f. The vertical reciprocable valve 15^g is provided, shown as in open position in Fig. 1 of the drawings. A bleed passage 15^h leads to the space beneath the valve 15^g and the latter is further provided with an upwardly extending stem 15ⁱ projecting above the valve block 15.

The operation of this valve is as follows: Air being supplied through the inlet 15^a to the chamber 15^c, it will flow through the passage 15^e to the chamber 15^d from whence it will flow out through the outlet 15^b. During this flow of air the pressure on the lower side of the valve 15^g is slightly less than on its upper surface and the valve will remain in open position due to this difference in pressure and the weight of the valve. When the inlet 11^d is closed by the plunger 20, flow through the passage 15^b ceases, and pressure beneath the valve 15^g immediately builds up through the medium of the bleed passage 15^h and, owing to the excess of pressure at the lower side of the valve 15^g, the latter is forced upwardly to the seat 15^f closing the flow of air through the passage 15^e until such time as the valve is positively moved back to open position.

Reciprocably mounted in the cylinder 11 is the piston or plunger 20 carrying the table 21, which may carry such other superstructure as is desirable, such as the pattern plate, lifting frame, etc., not forming a part of the present invention. The plunger 20 is provided with the central bore or cylinder portion 20^a closely fitting the upstanding post 12^a to reciprocate thereon. This upstanding post and the cylinder portion 20^a of the plunger 20 constitute the jolting cylinder while air is admitted from any desirable source through the port 12^d in the cylinder bottom for squeezing, the effect of this air, as is obvious, being to lift the plunger 20.

A cavity or elongated chamber 25 is provided in the plunger 20, see Figs. 1 and 4. The inner end of the valve block 15 projects into this cavity, as shown in Fig. 1. A stud 26 is carried by the plunger 20 over the valve stem 15ⁱ being so arranged as to strike the same on the downward movement of the plunger to positively move the valve 15^g to

open position. From the outlet 15^b leads a short duct or tube 27, see Figs. 2 and 4, to an inlet port 11^a on the wall of the cylinder 11, which in turn is in communication with the port 20^a in the plunger 20. The port 20^a also serves to provide communication between the cylindrical portion 20^a and the cavity 25. When the plunger 20 lifts sufficiently to close the inlet port 11^a, see 5 Fig. 3, for example, the air functions to immediately close the valve 15^c, cutting off further supply of air to the cylinder 20^a. Expansion of the entrapped air as well as the momentum of the arising plunger suff- 10 fices to carry the port 20^a into communication with the outlet 11^c whereupon a large portion of the compressed air in the cylinder 20^a escapes through the inlet 11^a and the weight of the plunger and mechanism supported 15 thereby is sufficient to drop the same to a jolting impact during which drop the stud 26 positively moves the valve stem 15ⁱ and valve 15^c to open position whereupon the cycle is repeated. By providing communica- 20 tion through the medium of the inlet 20^a between the cavity 25 and the cylindrical portion 20^a, the pressure on the former will be the same as that on the latter and consequently the pressure acting upon the up- 25 per portion of the valve stem 15ⁱ is that obtain- 30 ing in the jolting cylinder. Were this communication not provided the pressure on the cavity 25 would be substantially at- 35 mospheric and the pressure acting on the upper surface of the valve 15^c would be sufficient to prematurely blow the valve up to 40 position closing the outlet 15^b, thereby cutting off the supply of operating fluid to the jolting cylinder prematurely. 45 For squeezing, air is admitted, as explained above, from any desired source through the port 12^a, for example, and acts upon the bottom of the plunger 20 to lift the same until the supply is cut off and ex- 50 haust permitted by a manually-operated two- 55 way valve, for example, not shown. When the machine is jolting, the squeezing valve is left open to relieve and prevent suction beneath the plunger 20. 60 I find it desirable to leave the jolt inlet 15^a open to the atmosphere during the squeezing operation in order to eliminate suction in the cylinder 20^a, this control being permitted by a valve structure similar to 65 that shown in the patent to Krause 1,328,527, patented January 20, 1920.

It will be obvious that in my mechanism I provide two separate cylinders, although I use but a single main plunger and cylinder, but at the same time I so locate my jolt valve 15 that it may be readily removed and inspected or repaired without requiring the removal of the plunger 20, as in the case of prior devices. Similarly, it is not necessary 70 in my structure to carry air supply pipes or

ducts upwardly through the post 12^a and all of the necessary pipe is so located as to be readily accessible and not buried in the mechanism as in the cases of prior devices of this nature.

It will be obvious that my invention is susceptible of numerous modifications and improvements and I do not wish to be restricted to the form shown and described except as defined in the appended claims.

What I claim is:—

1. In a machine of the class described, a main cylinder provided with a central up- 80 standing post, a plunger reciprocably mounted in said cylinder and having a cylindrical portion reciprocating on said post, said plunger being recessed, an automatic jolting valve projecting into said recess, and means to supply fluid under pressure to the interior of said cylindrical portion of said plunger, said supply being automatically controlled by said jolt valve.

2. In a machine of the class described, a main cylinder provided with a central up- 90 standing post, a plunger reciprocably mounted in said cylinder and having a cylindrical portion reciprocating on said post, said plunger being recessed, an automatic jolting valve projecting into said recess, and means to supply fluid under pressure to the 95 interior of said cylindrical portion of said plunger, said supply being automatically controlled by said jolt valve, said cylindrical portion and said cavity being in communication.

3. In a machine of the class described, a cylinder having an internal upstanding post, a plunger reciprocably mounted in said cylinder and having a portion reciprocating upon said post, means to supply fluid under 105 pressure to said portion above said post, said means comprising an inlet, said plunger being further provided with a cavity, and a jolt valve projecting into said cavity and controlling the flow of operating fluid 110 to said inlet, said inlet being also in communication with said cavity.

4. In a machine of the class described, a cylinder having an internal upstanding post, a plunger reciprocably mounted in said cylinder and having a portion reciprocating upon said post, means to supply fluid under pressure to said portion above said post, said last-named means comprising an inlet, said plunger being further provided with 115 a cavity and jolt valve mechanism projecting thereinto and controlling the flow of operating fluid to said inlet, said cavity being in communication with the portion of said plunger reciprocating upon said post 120 whereby substantially the same pressure will obtain in both locations.

In testimony whereof I have subscribed my name.

PHILETUS W. GATES.
